SADIRON REST

William M. Cissell, near Louisville, Ky.

Application November 25, 1940, Serial No. 367,030

3 Claims. (Cl. 248—117.3)

My invention relates to a rest or stand upon which a sad-iron is lodged between pressing operations and for storage.

The main object of my invention is to provide a serviceable and safe sad-iron rest that will eliminate the fire hazard resulting from an over-heated electric iron, which condition may develop from a faulty thermostat.

Another object of my invention is to provide a heat conserving air-cooled sad-iron rest.

A further object of my invention is to provide a durable sad-iron rest that can be manufactured in large numbers at low cost.

A feature of my invention is to provide for facile repairing should such be required.

These and other objectives are accomplished in the embodiment of my invention shown in the annexed drawing and described in the accompanying specification, and particularly pointed out in the appended claims.

In the annexed drawing:

Figure 1 is a plan view of one embodiment of my invention.

Figure 2 is a section taken along line 2, 2 of Figure 1.

Figure 3 is a section taken along line 3, 3 of Figure 1.

In the drawing the iron-rest is illustrated as having a rectangular contour, however, it may be oval, hexagonal, or of any other desired form. Numeral 5 designates a relatively thick plate of heat insulating material such as "Transite," composed of asbestos and a binder to provide a strong hard board having smooth surfaces capable of withstanding the relatively hard usage encountered in a commercial laundry using sad-irons continuously during working hours. In addition to functioning as a sad-iron rest-plate and a heat insulator, plate 5, by reason of it being flat and having an area in excess of the face of the sad-iron, serves to conserve heat by preventing air currents from circulating over the pressing face of the sad-iron, and further serves as a beeswax carrier. Since plate 5 is made from smooth Transite board, and secured to the base by merely pressing it into the panel frame formed by the projecting flange 6 and top 7 of the base, either face of the board can be used for contact with the sad-iron. Thus, after long service has impaired one face, plate 5 can be reversed. Access to screw holes 8 may be had by removing plate 5 from the frame, and these screw holes are provided for attaching the base to an ironing board or other object by screws, not shown.

The upper surface of the top 7 is provided

with teats 9 functioning as perches for the plate 5, which teats are formed by heavily indenting the under surface of the top 7. Likewise, the flange 6 is similarly formed at 10 with teats or prongs. Thus, an effective ventilating space is provided between the perimetrical edges of the plate 5 and the flange 6, and likewise between the under surface of the plate 5 and the upper surface of the top 7. Therefore, it will be observed that provision is made for the circulation of air currents through the space provided between the base and the plate, thus completely protecting said base and ironing-board upon which it is mounted.

15 Sad-iron rests produced commercially in accordance with the accompanying drawing have been repeatedly subjected to the maximum heat liberated by an electric, laundry sad-iron having its thermostat control disconnected, and retain 20 under the influence of the extreme heat of the iron until the heating element of the iron destroyed itself, without any apparent impairment of any part of the iron-rest.

Another protection for the sad-iron resides 25 in placing the top surface of plate 5 well above the top edge 11 of the flange 6, so that the ironing surface of the sad-iron cannot be marred by contacting the metal base. Plate 5 is literally "set" into prongs 10 as a lapidarist mounts a jewel, except that its prongs, being a part of flange 6, are sprung for the admission or extraction of the plate.

As mentioned at the outset, a rectangular contour for the sad-iron rest has been illustrated, 30 but it must be understood that modifications, and other combinations of the physical elements can be organized to employ the principles disclosed herein. Therefore, I wish to be limited only by the following claims.

40 I claim:

1. A sad-iron rest consisting of a horizontal base having a perimetrical flange extending substantially vertically-upwardly from the marginal edges of the said base; a plate of heat insulating 45 material disposed upon the said base and within the said perimetrical flange, the said plate having its marginal edges substantially congruent with the corresponding marginal edges of the said base; and a plurality of projections extending laterally-inwardly from opposing faces of the said flange, and frictionally engaging corresponding marginal edges of the said plate, for frictionally securing the said plate to the said base.

2. A sad-iron rest consisting of a horizontal

base having a perimetrical flange extending substantially vertically-upwardly from the marginal edges of the said base; a plate of heat insulating material disposed upon the said base and within the said flange, the said plate having its marginal edges spaced laterally-inwardly from, and substantially parallel with, corresponding faces of the said flange; and a plurality of projections extending laterally-inwardly from opposing faces of the said flange, and frictionally engaging the corresponding marginal edges of the said plate, for frictionally securing the said plate

to the said base in the aforesaid spaced relation with the said flange.

3. A sad-iron rest consisting of a sheet-metal base having a perimetrical flange struck therefrom; a plate of heat insulating material disposed upon the said base and within the said flange; and a plurality of notches struck laterally-inwardly from opposing faces of the said flange, and frictionally engaging corresponding marginal edges of the said plate, for frictionally securing the same to the said base.

WILLIAM M. CISSELL.
